CLAIM

The ornamental design for a blank for a container, as shown and described.

DESCRIPTION

FIG. 1 is a top plan view of a blank for a container showing my new design; the bottom plan view being a mirror image;

FIG. 2 is a front elevation thereof;

FIG. 3 is a top plan view of a modified embodiment of FIG. 1; the bottom plan view being a mirror image; and FIG. 4 is a front elevation of FIG. 3.

The blank is of conventional thickness.

FIG. 1.

FIG. 2.

FIG. 3.

FIG. 4.
